UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

HAND-GENERATOR FOR HARMONIC SIGNALING SYSTEMS.

1,032,688.

Specification of Letters Patent. Patented July 16, 1912.

Original application filed February 1, 1907, Serial No. 355,207. Divided and this application filed March 16, 1907. Serial No. 362,744.

To all whom it may concern:

Be it known that I, RAY H. MANSON, a citizen of the United States, residing at Elyria, in the county of Lorain and State of Ohio, have invented certain new and useful Improvements in Hand-Generators for Harmonic Signaling Systems, of which the following is a specification, reference being had therein to the accompanying drawing.

10 This invention relates to telephone systems and especially to harmonic signaling systems.

It has for its object the production of means whereby an annunciator or indicator 15 may be actuated from a substation or other point on a line, without actuating any of the ringers at the subscribers' stations.

The invention is particularly applicable to what are known as rural or farmers' 20 lines, whereof the length and resistance are too great to permit of the use of common battery, and, therefore the old fashioned magneto hand generator is employed for purposes of signaling. At the central station 25 constituting the terminus of such a line the operator is provided with ringing generators as used in all systems; and at the substations, the hand generators are located usually in open bridges of the line, closed 30 when signaling.

When ordinary hand generators are used in the manner indicated, with harmonic ringers, there is a strong tendency for the 35 low frequency ringers to be actuated every time a subscriber is calling central. By low frequency ringers in this case I particularly refer to the 16 and 33 cycle ringers, where the complete set of frequencies employed 40 are: 16, 33, 50, 66. Of course these frequencies may be made anything desired, but are referred to herein because they are standard.

The present design consists specifically of a commutator arrangement adapted to regulate 45 the current from the hand generator, so as to prevent its ringing any of the bells at the substations when signaling the exchange for a connection or when clearing out.

50 I have found that an ordinary alternating current generator will operate the 16 cycle bell even when the line terminates in a 100 ohm annunciator at the switchboard. This is true when a low voltage generator is used,

such as a three bar alternating current generator with one magnet reversed so as to neutralize one of the other magnets and give in effect a one bar generator. I have also found that three bar direct current generators and pulsating current generators will 55 operate the low frequency harmonic ringers. A special drum wound armature with a large number of commutator segments will not do this but the construction cannot be carried to this point on account of expense 60 in manufacture and in carrying special stock therefor.

Instead of such an armature and commutator, I prefer to employ a special commutator having one or more contact points, 70 wired in series with the terminals of the generator, which is arranged to give alternating current. The form of commutator actually employed by me in practice has only one point, and it breaks up the alternating current into widely separated periods 75 of a single impulse or wave each, so that there are no alternations in continuity to start the low frequency bells to vibrating. The single point of the commutator makes 80 contact only once during a complete revolution of the armature, and the duration of contact is very short. The best results are obtained in an ordinary sized generator with a contact 1/16" long on a 5/8" or 85 3/4" diameter commutator.

The current thrown on the line by this commutator apparently has a very high and peaked curve, and while not of sufficient volume or strength to operate the ringers it 90 is sufficient to operate the switchboard annunciators with ease.

By the use of my new generator I am enabled to employ a high wound bridging switchboard annunciator, thereby preventing 95 the shunting of voice current when two parties on the line are talking.

This application is a division of my former application, Serial No. 355,207, filed February 1, 1907.

100 My invention is illustrated in the accompanying drawings, in which—

Figure 1 is a side elevation of my generator. Fig. 2 is an end elevation thereof. Fig. 3 is a perspective of the separated parts 105 of the commutator and a portion of the armature spindle. Fig. 4 is a sectional view of one end of the armature spindle and the

commutator. Fig. 5 is a diagram of a current curve. Fig. 6 is a diagrammatic view showing a line, a switchboard drop, three substation ringers bridged across the line, 5 and my improved generator also bridged at a fourth station. Fig. 7 is a similar diagram with the substation ringers in ground taps. Figs. 8, 9 and 10 are detail views of 10 a modified form of my generator in which the commutating mechanism is mounted on the crank shaft.

Referring to Fig. 1, 1 designates the field magnets of the generator, of which there are three and to which is secured the plate 2 having apertures at 3 to receive bolts for attachment to a support. The pole pieces 4 of the field magnets have secured to them at each end a pair of supporting plates 5 and 6 each provided with an extension in 20 which is journaled the main shaft 7. Carried by the main shaft and meshing with a pinion 8 on the armature shaft 9 is the main or driving gear wheel 10 operated in the usual manner by the crank 11. The line 25 contacts 12 and 13 are carried upon a frame 14 secured above the armature shaft 9 on the plate 5 and so positioned as to be engaged by the projecting insulated end 15 of the shaft 7 when the generator is operated. The 30 end of the armature shaft 9 is hollowed out and is provided with an insulating bushing 16 in which the commutator spindle 17 is secured by means of the pin 18 which passes through a bushed opening in the shaft 9 and 35 is insulated from the shaft by the collar 19. To the end of the commutator spindle 17 is secured the commutator K comprising a pair of metallic disks 20 having projecting teeth 21 and separated by the disk of 40 insulation 22. This disk of insulation is provided with a notch 23 which lies between the two teeth 21 of the disks 20, so as to insure positive contact with the brush 24 carried by the frame 14. The parts 20 and 45 22 are secured together by bolts 25 passing through all the disks and electrically connecting the disks 20.

The frame 14 is electrically in connection with the field magnets and supports an arm 50 27 insulated therefrom but which is in electrical connection with the spring 13. This arm is provided with a line terminal binding post 26. The other line terminal binding post is indicated at 28 and is formed 55 upon the plate 5. The brush 24 normally bears against the insulation 22 until the shaft is turned sufficiently to bring the lugs 21 of the disks 20 in contact therewith at which time the aperture 23 allows the spring 60 26 to engage said lugs. The brush 24 being in engagement with the spring 12 and the spring 13 being at that time forced over into engagement with the spring 12 by the operation of the crank 11 the circuit is thus 65 completed through the generator. This cir-

cuit may be traced as follows: binding post 26, arm 27, spring 13, spring 12, brush 24, teeth 21, commutator disks 20, connector 17, armature winding, frame of generator, end plate 5 to binding post 28. From the time 70 of last contact of the teeth 21 with the brush 24 there is no current whatever passing out over the line as the circuit is broken by reason of the brush engaging the insulating disk 22 and the E. M. F. in the generator piles up so that when the lugs again contact with the brush a high peaked wave as shown in Fig. 5 is thrown on the line through the bridge wires. This current is not of sufficient volume or strength or of long enough 80 duration to operate the low frequency bells but is strong enough to operate the switchboard drop. 75

As shown in Fig. 8, I may arrange the commutating mechanism upon the crank 85 shaft 7. In this figure only enough of the generator is indicated to show the arrangement of the commutating mechanism. The shaft 7 carries upon its left-hand end a collar 30, which is provided with a projecting 90 tooth or lug 31 adapted to engage the spring 32 as the shaft 7 is rotated. The spring 32 is secured by screws 33 to an insulating support 34, which in turn is supported from the frame of the generator. The block of insulation 34 also supports the springs 12 and 13, which are adapted to perform the same function as already described. The brush 24 is supported from the insulating block 34 in electrical contact with the spring 12 95 and is adapted to bear upon a metallic disk 35 secured to the pin 17. The pin 17 is supported from the armature shaft 9 and serves in the same manner to perform the same function as set forth in connection with the 100 form of generator described above. As shown in Fig. 9, the collar 30 may be equipped with two teeth or lugs 31a. In this modification the circuit through the generator may be traced as follows: binding 110 post 26, spring 13, spring 12, brush 24, disk 35, pin 17, to and through the armature winding, through the armature shaft, the frame of the generator and the crank shaft to collar 30, spring 32, and thus through one 115 of the screws 33 to the other line connection.

In Fig. 6 I have shown four stations, A, B, C and D, the first three of which are indicated by the bells B' and the condensers C' and the last one of which is indicated by the generator heretofore described, in a diagrammatic way. S points out the switchboard drop at the central office, which when the generator is operated indicates to central that a call has been made and connection is desired. The binding posts of the generator are connected to the line conductors, as a result of which, when the generator is operated, current takes the following 125 path: from one of the binding posts, through 130

one line conductor to the signal S, back by the other line conductor to the other binding post of the generator and thence through the generator by a path already traced. The 5 cord circuit and other apparatus I have not shown as it is deemed unnecessary to the understanding of this invention.

In Fig. 7 I have shown a similar system to that of Fig. 6 except that the stations

10 $A^2, B^2, C^2, D^2, E^2, F^2$ and G^2 are grounded.

As before stated, when a generator as, for instance, that at station D in Fig. 6 was operated the low frequency bells of other subscribers on the same line were operated, 15 resulting in confusion at the substations and also at the central office because the switch-board drop and the low frequency bells were operated simultaneously.

In a modified form of my generator the 20 commutator is mounted on the crank shaft and may be fitted with one or more teeth with the result that without changing the gear ratios ordinarily used in standard generators and without special formation of 25 the commutator, impulses of low frequency may be delivered from such generator and that such frequency will not be adapted to operate harmonic ringers. In connection with this form of generator, I have found, 30 however, that without specially designing the gears, the impulses delivered are irregular in value and that in many cases a large number of turns of the crank is required between impulses of maximum electromotive 35 force. Thus there is an opportunity for inefficient operation of the apparatus designed to be actuated by such generator which may, however, be overcome by constructing the commutator on the crank shaft 40 with but one tooth, and by using gears of even ratio. Such an arrangement however does not employ standard gearing, and for this reason I prefer the arrangement already described, in which the commutator is located 45 on the armature shaft and has but a single tooth, making contact but once for a short space of time during each rotation of the armature. The point at which this shall occur is definitely fixed, so as to give the 50 proper current effect.

In considering the invention it must be borne in mind that for all harmonic signaling of successful commercial type, it takes

more than a momentary impulse to start vibration of a ringer. This however is also 55 true in many cases of resonance. The trot of a dog will not at first start a bridge to vibrating, but if maintained for a few seconds it will inevitably do so by reason of the cumulation of energy. It is upon this 60 principle that my present invention is based.

Fig. 5 shows a current curve approximating the wave form produced in my generator. Owing to the sudden discharge when 65 the momentary contact is made at the commutator, there is a jerk or peak which while it runs up high above the neutral line, is of small area, and the amount of energy represented is correspondingly small. 70

While I have shown a bridging circuit, it is to be understood that the generator is useful in other circuits, and also that this circuit may be used with other specific forms of generator, so long as the essential principle is employed, of thus preventing resonant effects. All non-essential changes and departures I include within the scope of my 75 claims.

Having thus described my invention what 80 I claim and desire to secure by Letters Patent is—

1. In a generator for signaling systems, a field magnet and an armature in operative relation thereto, means for driving such 85 armature, a commutator consisting of a pointed disk connected to such armature, a brush adapted to bear upon the commutator and means for preventing contact between such brush and such disk except at such 90 pointed portion.

2. In a generator for signaling systems, a field magnet and an armature in operative relation thereto, means for driving such armature, a commutator consisting of a disk 95 connected to such armature and having a projecting point, a brush adapted to bear upon such commutator, and means for preventing contact between such brush and such disk except at such projecting point. 100

In testimony whereof I affix my signature in presence of two witnesses.

RAY H. MANSON.
